HYDRAULIC PUMP OR MOTOR

Elek K. Benedek, Bucyrus, Ohio

Application October 21, 1935, Serial No. 45,908

12 Claims. (Cl. 103—161)

This invention relates to rotary radial piston hydraulic pump and motors, the principal object being to provide a highly efficient and compact pump or motor of this character, comprised of simple and rugged parts which may be manufactured economically from readily available materials.

Another object is to provide a pump or motor employing a minimum of parts and of which the parts may be assembled and disassembled more easily and manufactured by quantity methods with accuracy assuring fitting into proper operating relations.

Another object is to provide an improved barrel mounting, a simplified and rugged reactance means for cooperation therewith, and a simplified positive coupling therebetween.

Still another object is to guide the piston heads efficiently and to effect load transmission between the barrel and rotary reactance by rolling friction instead of sliding friction.

Other objects and advantages will become apparent from the specification wherein reference is made to the drawings, in which:

Fig. 1 is a horizontal longitudinal sectional view of a pump or motor embodying the principles of the present invention;

Fig. 2 is a vertical, cross sectional view and is taken on a plane indicated by the line 2—2 in Fig. 1, the barrel thereof being shown in a slightly different rotated position than in Fig. 1;

Fig. 3 is a longitudinal sectional view of the reactance means illustrated in Fig. 1;

Fig. 4 is a sectional view taken on a plane indicated by the line 4—4 in Fig. 3; and

Fig. 5 is a fragmentary plan view of the barrel and flange, viewed from the line 5—5 in Fig. 2.

For the purposes of illustration the present structure will be described as a pump, its operation as a motor being readily apparent therefrom.

Referring to the drawings, the pump structure is enclosed in a rigid weight supporting housing 1, having an annular wall portion 1a terminating at one end in a radial flange wall 1b, the flange 1b, in turn, terminating inwardly in a rigid hub portion 1c, in which the main fluid circuit ports for connecting the pump to an external fluid circuit are provided, as will later be described. The opposite end of the housing 1 is closed by a rigid cover 2 which may be secured to the end wall of the portion 1a by suitable bolts, or other means, not shown.

A rigid valve pintle 3, having an enlarged shank portion 3a, is mounted at its shank in the hub portion 1c of the housing, the shank being fixedly

secured in a suitable axial bore formed in the hub 1c. The pintle extends from the shank portion 3a into and coaxial with the housing portion 1a and has a portion adjacent the shank providing a large diameter bearing race 3b. On the opposite or free end of the pintle 3 is a bearing race 3c. Between the race portions of the pintle is a valve portion 3d which is tapered toward the free end of the pintle. In the pintle valve portion 3d are reversible valve ports 4 and 5 which are separated from each other by suitable valve or timing bridges, as better illustrated in Fig. 2.

The valve port 4 is in communication with longitudinally extending ducts 6 which are formed in the pintle and communicate, in the shank portion 3a thereof, with one reversible main fluid port of the pump. The other valve port 5 is in communication with longitudinal ducts 7 which also are formed in the pintle and communicate in the shank portion 3a with the other reversible main fluid port of the pump. Thus the ducts 6 and 7, with the valve ports 4 and 5, and the main ports, not shown, in the shank portion 3a of the pintle, form the internal fluid circuit in the usual manner. Due to the large shank portion 3a and race portion 3b and taper of the pintle, the ducts 6 and 7 can be drilled in converging direction so that the pintle provides a substantially constant strength beam.

Mounted within the housing 1 in coaxial relation with respect to the pintle 3 is a cylinder barrel or rotor 10 having a tapered axial bore the wall of which is complementary to and hydraulically fits the valve portion 3d of the pintle, the end of the bore adjacent the free end of the pintle being sealed for retaining fluid for hydrostatic balance of the pintle, as will later be described.

The barrel 10 has a radial flange 11, preferably forged integral therewith, the flange having a plurality of circumferentially spaced radial guideways 11a. In the barrel, in the zone of the flange and aligned one with each guideway, are radial cylinders 12, each of which has a cylinder port 13 for cooperation successively with the ports 4 and 5 of the pintle subsequent upon rotation of the barrel.

For the purpose of constraining the barrel and pintle to positive coaxial relation with positive, accurate radial capillary clearance between the valve portion 3d of the pintle and bore wall of the barrel, the barrel is provided with internal bearing race surfaces 10b and 10c, these races being aligned radially with the races 3b and 3c respectively, of the pintle. Sets of capillary cageless needle rollers 15 and 16 respectively are in-

terposed between the radially aligned races of the pintle and barrel. The races 3b and 3c are preferably in the form of annular troughs formed on the pintle, the end walls of the troughs constraining the respective sets of needle rollers in proper position longitudinally of the pintle. By constraining the barrel and pintle to fixed coaxial relation with positive radial clearance space between the pintle valve portion and barrel bore wall by the capillary rollers, any inaccuracies in manufacture which would otherwise cause misalignment of the pintle and barrel are prevented.

In order to maintain the pintle in hydrostatic balance, the pintle is provided with a central duct 11 which is in communication with the instantaneous pressure ducts of the internal fluid circuit, and discharges through the free end of the pintle into the dead end of the barrel bore, as more fully described in my co-pending application, Ser. No. 754,753, filed November 26, 1934. Thus the operating pressure fluid is continuously fed into the dead end bore of the barrel 10 and flows into the capillary clearance space between the pintle valve portion and barrel bore wall and maintains fluid at line pressure therebetween. By maintaining hydrostatic balance in this manner, a heavy hydraulic pressure thrust is created against the dead end of the barrel bore and urges the barrel to the right in Fig. 1. For notwithstanding this thrust and providing for accurate adjustment of the barrel longitudinally of the pintle so as to maintain the proper clearance space between the valve portion 3d and barrel bore wall, the barrel is rotatably mounted in the housing on sets of "Tyson" tapered cageless rollers 18 and 19 respectively. For effecting the proper mounting of the barrel in the rollers 18 and 19, the end portion of the barrel is in radial alignment with the race 10b to form a suitable annular shoulder 20 and radial shoulder 21. The shoulders 20 and 21 cooperate to accommodate the inner race 22 of the set of rollers 18.

The flange portion 1b of the housing is correspondingly provided with an internal shoulder 23 and radial shoulder 24 which fixedly accommodate the outer stationary race 25 of the set of rollers 18. As illustrated in Fig. 1, the rollers 18, due to their tapered form and angular disposition, are operable to resist radial load and axial thrust of the barrel toward the shank 3a. At the opposite end of the barrel is a corresponding annular shoulder 26 and radial shoulder 27 accommodating the inner race 28 of the set of rollers 19. The end cover 2 is provided with an internal annular shoulder 29 and radial shoulder 30 which accommodate the outer race 31 of the set of rollers 19. The set of rollers 19 is disposed so as to resist radial load and thrusts of the barrel in the direction opposite to the set of bearings 18, especially that caused by the pressure fluid in the barrel bore.

Near its outer margin the cover 2 is provided with an annular shoulder 32 coaxial with the shoulder 29. The portion 1a of the housing is correspondingly provided with an accurately positioned shoulder 33 cooperable with the shoulder 32 for locating the end cover 2 in proper position on the housing.

By the introduction of proper shims between the end of the housing portion 1a and marginal face of the cover 2 the barrel 10 may be adjusted axially for providing the proper tightness of the bearings 18 and 19. By eliminating undue radial slackness in the bearings 18 and

19, the barrel is supported thereby. Accurate position in the casing and movement of the barrel axially in the direction to tighten the bearings 18 and 19 reduces the radial clearance between the tapered pintle and the tapered valve bore wall and also centers the barrel more accurately with respect to the pintle so that the radial clearance is more uniform. The bearings 15 and 16, in turn, do not resist axial movement of the barrel but constrain the pintle and barrel to coaxial relation in all adjusted positions and under hydrostatic deflecting forces so that, whatever total radial clearance is provided, it will be uniformly distributed circumferentially of the valve pintle. The bearings 15 and 16 also draw the pintle to proper coaxial relation in the barrel so as to overcome manufacturing inaccuracies. Thus there is maintained proper radial clearance between the valve portion 3b and barrel bore wall so that wear may be compensated.

Certain advantages of the specific structure illustrated should be noted.

First, by setting the housing 1 in a suitable rotary carrier, the bore for the pintle shank 3a may be drilled in the hub 1c and the shoulders 23 and 33 may be formed at the same setting so that all circular fitting parts are absolutely concentric or coaxial with respect to each other. Correspondingly, the barrel may be mounted in a suitable carrier by its impeller shaft and the shoulders 20 and 26, the races 10b and 10c, and the tapered valve portion of the barrel bore formed at the one setting so that all parts thereof are in coaxial relation. Next, the end cover 2 is turned at a single setting with the shoulder 32 and shoulder 29 in absolute coaxial relation.

Thus, when the parts are assembled, all are necessarily in coaxial relation with respect to each other and accuracy in manufacture and assembly is assured.

Referring next to the pistons and reactance means of the pump, radial pistons 40 are carried in the cylinders respectively. Each of the pistons 40 has a crosshead 41 with cylindrical end walls, axes of the end walls being parallel to the axis of the associated piston and having flat lateral faces. The radial guideways 11a have cylindrical guide walls, as better illustrated in Fig. 5, for engaging the cylindrical end walls of the heads 41 and accommodate the piston heads for reciprocation radially of the barrel while relieving the pistons 40 from torque transmission and preventing lateral vibration and misalignment of the heads. Each piston crosshead 41 has a transverse bore in which is accommodated an operating cross pin 42. The pin 42 is rotatably mounted in the bore of the associated crosshead on capillary cageless needle rollers 43 which are retained in the crosshead bore by suitable retaining washers, not shown. Each crosspin 42, in turn, has a large diameter central portion substantially coextensive with the cross head and reduced diameter end portions 42a coaxial with the larger central portion so as to present radial guide shoulders 42b, at the juncture of the central and reduced end portions, the shoulders merging with the reduced end portions 42a with a very slight fillet.

For cooperation with the pins 42, there is provided an adjustable rotary reactance means comprising a pair of mated, oppositely positioned, symmetrical one-piece reactance rings 45, each of which has an annular reactance groove 46 open toward the piston heads for receiving the

ends 42a of the cross pins and forming a reactance track therefor. The adjacent faces 45a of the rings 45 extend radially and lie snugly alongside the flange 11 and lateral flat faces of the crossheads 41. The radius of curvature between the radially inward track walls of the grooves 46 and radial face 45a of the ring 45 are slightly greater than the radius of the fillets between the shoulders 42b and end portions 42a of the 10 crosspins for effecting proper guiding relation with the crosspins to prevent skewing of the pins in the grooves.

The rotary reactance rings 45 are mounted on heavy duty bearings, such as ball bearings 47, 15 within a pair of stator rings 48, the ball bearings operating in suitable grooves in the rings 45 and 48. The ball grooves are of slightly greater radius than the balls so that slight axial self-adjustment of the rings 45 is provided. Each 20 reactance ring 45 and its cooperating stator ring 48 is a separate and complete self-contained ball bearing assembly, the ring 48 being the outer race and the ring 45 being the inner race. The races 45 and 48 are formed with bearing grooves 25 for receiving the balls 47 so that the sides of the groove cooperate with the associated balls for constraining the inner and outer races of each assembly from relative axial separation. Thus a pair of axially separable reactance sub-units 30 are provided which together form the reactance means of the pump.

The rings 48 are provided at their adjacent faces with accurately formed and machined surfaces, as indicated at 49, so that they may be 35 positioned readily in coaxial relation with respect to each other. They are likewise provided with sets of aligned longitudinal bores accommodating suitable bolts 50 for securing drawing and clamping the rings 48 together to form 40 a unitary structure, lock washers 51 being interposed between the heads of the bolts and corresponding ring 48 to maintain the rings rigidly fixed in position with respect to each other. Each 45 of the rings 48 is provided on its outer surface with parallel tangential slide bearing surfaces 48a at diametrically opposite positions for cooperation with corresponding slide bearing surfaces within the annular wall portion 1a of the housing, as better illustrated in Fig. 2, for mounting 50 the reactance stator rings 48 so that they may be shifted as a unit to different positions of eccentricity with respect to the pintle axis while constrained to positions in which their axis is parallel to the pintle axis and in a plane 55 through the pintle axis and dead center line of the pintle bridges. Suitable control rods 52 are secured to the rings 48 and extend through suitable bores in the housing portion 1a so that the stroke of the pump may be adjusted from the 60 outside.

In some instances it is desirable, especially upon starting and stopping, that a positive driving connection be provided between the barrel and reactance rings 45. For this purpose holes 65 55 are provided in the flange 11, the holes being evenly distributed midway between adjacent pistons and being positioned radially in the zone of the grooves 46. The rings 46 are provided with dead end pin receiving bores 56 which open 70 through the end walls of the grooves 46, the bores 56 of the two rings being arranged in pairs and the bores of each pair being aligned axially of the rings with respect to each other. Cylindrical dowel pins 57 are disposed within the pairs 75 of aligned bores 56 respectively, and extend

through the openings 55, and are held in position consequent upon securing the rings 48 in fixed axial position with respect to each other. The dowel pins 57 fit into the associated bores 56 with slight clearance radially of the pins so as to permit very slight and limited relative rotation of the rings 45 with respect to each other but this relative rotation is not sufficient to be noticeable and appreciably affect the central portion of the dowel pins where they engage the 10 barrel flange. This clearance is only sufficient to permit light capillary oil films to form around the ends of the pins 57 and the portions of the pins received in the bores 56 so as to damp vibration thereof hydraulically and thus reduce the 15 noise incident to operation. The openings 55 are of sufficient diameter to permit the maximum eccentricity of the rings relative to the barrel in either direction from the dead center position. By this arrangement standard drill stock rod may 20 be used for the pins 57 and merely cut to length, ground at the ends and inserted. Thus the entire reactance assembly, including the dowel pins 57, is held together by bolts 50. Correspondingly, the piston cross pins 42 are held in proper 25 operating position thereby and rotation of the pistons about their own axes is prevented by the shoulders 42b. Due to the capillary cageless rollers 43, the frictional resistance to rotation of the pins about their own axes in the bore of the 30 crossheads is less than the rolling frictional resistance of the reduced end portions 42a in the operating grooves 46 with the result that sliding of the end portions 42a in the grooves is prevented. 35

By forming the reactance in this manner, both the stator and rotor can be made of forgings so as to provide both good race qualities and resistance to hydraulic load while at the same time reducing the radial dimension of the structure. 40 The rings 45 are also sturdy enough to offer substantially uniform resistance to elastic deformation and permanent deformation. All operating and relatively movable surfaces of each moving part are ground, polished and nitrided, and all such parts are preferably made of nitr alloy, having a Brinell hardness of about 1000. Thus not only is wear eliminated or greatly reduced but also foreign matter which comes in contact with the working parts is itself reduced and worn 45 away instead of causing wear or damage to the parts. By forming the rotary reactance means in the manner provided, the different problems of assembly and disassembly are eliminated. Obviously, all that is necessary to be done is to 50 remove the end cover 2 of the housing, remove the control rods 52 and the entire operating assembly can be removed from the housing. By removing the bolts 50 the reactance means can be separated and any part that is worn may be 55 replaced. Furthermore, both halves of the reactance means can be formed identically so that any half will properly match and cooperate with any other half. Again, in the case of any damage to any part of the reactance means or any 60 roller or ball thereof, it is not necessary to replace the entire reactance but only the half that might be damaged. 65

It is apparent from the foregoing description that each part of the structure may readily be 70 formed from readily available materials by simple machining operations so that the resultant structure is both simple, durable, easily serviced and economical to manufacture, the number of working parts being reduced to a minimum. 75

Having thus described my invention, I claim:

1. A rotary reactance unit for a pump or motor of the character described, comprising a pair of matched coaxial stator rings, each ring providing an outer bearing race, means detachably connecting the rings rigidly together in said coaxial and end to end relation, with their mutually adjacent faces abutting each other, a pair of matched reactance rings correspondingly mounted one reactance ring within and coaxial with each stator ring, each reactance ring providing an inner bearing race, sets of rolling bearing elements interposed one set between and in direct rolling engagement with each stator ring and associated reactance ring as races for rotatably supporting the associated reactance rings, said sets of bearings cooperating with the associated reactance rings to constrain the associated rings to fixed axial and radial position with respect to the stator rings, whereby each stator ring and associated reactance ring and elements provide a self-contained anti-friction bearing assembly, said reactance rings having inner radial end walls spaced apart axially when the stator rings are secured together, whereby portions of radial pistons to be cooperated with the rings may be accommodated therebetween, and said spaced inner end walls having aligned reactance grooves respectively therein opening toward the opposite one of said rings, whereby piston actuating pins of the said pistons to be associated therewith as the rings are drawn axially toward each other may be received axially in the grooves, said grooves being disposed closer to the axis of rotation of said stator rings and said reactance rings than said roller elements.
2. A rotary reactance unit for a pump or motor of the character described, comprising a pair of matched coaxial stator rings, means for detachably connecting the rings rigidly together in end to end relation, a pair of matched reactance rings mounted one reactance ring within and coaxial with each stator ring, radially aligned circumferential recesses in the inner circumferential surface of each stator ring and the outer circumferential surface of its associated reactance ring, roller elements in the aligned recesses directly cooperating with the associated recesses to constrain each stator ring and its associated reactance ring to fixed axial and radial position with respect to each other and providing a self-contained anti-friction bearing assembly, said reactance rings having inner radial end walls spaced apart axially when the stator rings are secured together, whereby portions of radial pistons to be cooperated with the rings may be accommodated therebetween, and said spaced inner end walls having aligned reactance grooves respectively therein and opening toward the opposite one of said rings, whereby piston actuating pins of the said pistons to be associated therewith as the rings are drawn axially toward each other may be received axially in the grooves, the grooves being closer to the common axis of said stator rings and said reactance rings than said roller elements.
3. A rotary reactance unit for a pump or motor of the character described, comprising a pair of matched axially separable coaxial stator rings, means for detachably connecting the stator rings rigidly together in end to end abutting coaxial relation, a pair of matched reactance rings correspondingly mounted one reactance ring within and coaxial with each stator ring, sets of rolling bearing elements interposed one set between

each stator ring and associated reactance ring for rotatably supporting the associated reactance rings, said sets of bearings cooperating with the associated rings to constrain the associated rings to fixed axial and radial position with respect to each other, said reactance rings having inner radial end walls spaced apart axially when the stator rings are connected together, whereby portions of radial pistons to be cooperated with the rings may be accommodated therebetween, and said spaced inner end walls having aligned reactance grooves therein extending parallel to the common axis of the rings and opening toward the opposite one of said rings, whereby actuating pins of the pistons to be associated therewith as the rings are drawn axially toward each other may be received in the grooves, each of said reactance rings having a plurality of bores extending parallel to their common axis and opening toward and aligned with the other, torque transmitting dowel pins received axially, one in each pair of said aligned bores and retained therein by the reactance rings, whereby the reactance unit may be readily assembled and disassembled axially.

4. In a rotary, radial piston pump or motor, a rotatable barrel having a plurality of radial cylinders, a radial flange on the barrel in the plane of the cylinders, and having radial guideways respective to the cylinders, valve means for the cylinders, pistons in the cylinders respectively and having heads operating in said guideways, thrust pins carried by said heads and having end portions extending laterally therefrom at each face of the flange, and rotary reactance means eccentric to the barrel and cooperable with the thrust pins for actuating the pistons, said reactance means comprising a pair of coaxial stator rings detachably secured together in end to end abutting relation at the plane of the pistons and axially separable from each other, means for detachably connecting said rings to each other, reactance rings anti-frictionally mounted one in each stator ring and spaced axially from each other and accommodating the barrel flange and piston heads therebetween, reactance grooves in said reactance rings opening toward the barrel flange and receiving the laterally extending end portions of the pins for cooperation therewith to actuate the pistons, holes in said barrel flange positioned radially of the flange in alignment with the grooves, bores in each reactance ring in the groove thereof and opening toward the opposite reactance ring and extending parallel to the axis of rotation, each bore being aligned with a bore of the opposite reactance ring, and cylindrical dowel pins extending through the barrel flange holes and received at their ends, one in each pair of aligned bores, and held in position by the reactance rings.

5. In a rotary, radial piston pump or motor, a rotatable barrel having a plurality of radial cylinders, a radial flange on the barrel in the plane of the cylinders, and having radial guideways respective to the cylinders, valve means for the cylinders, pistons in the cylinders respectively and having heads operating in said guideways, thrust pins carried by said heads and having end portions extending laterally therefrom at each face of the flange, and rotary reactance means eccentric to the barrel and cooperable with the thrust pins for actuating the pistons, said reactance means comprising a pair of coaxial stator rings detachably secured together in end to end abutting relation at the plane of the pistons and

- axially separable from each other, means for detachably connecting said rings to each other, reactance rings anti-frictionally mounted one in each stator ring and spaced axially from each other and accommodating the barrel flange and piston heads therebetween, reactance grooves in said reactance rings opening toward the barrel flange and receiving the laterally extending end portions of the pins for cooperation therewith to actuate the pistons, holes in said barrel flange positioned radially of the flange in alignment with the grooves, bores in each reactance ring in the groove thereof opening toward the opposite reactance ring and extending parallel to the axis of rotation, each bore being aligned with a bore of the opposite reactance ring, cylindrical dowel pins extending through the barrel flange holes and received at their ends, one in each pair of aligned bores, and held in position by the reactance rings, each of said dowel pins being accommodated in said bores with slight radial clearance.
6. In a rotary, radial piston pump or motor, a rotatable barrel having a plurality of radial cylinders, a radial flange on the barrel in the plane of the cylinders, and having radial guideways respective to the cylinders, valve means for the cylinders, pistons in the cylinders respectively and having heads operating in said guideways, thrust pins carried by said heads and having end portions extending laterally therefrom at each face of the flange, and rotary reactance means eccentric to the barrel and cooperable with the thrust pins for actuating the pistons, said reactance means comprising a pair of coaxial stator rings detachably secured together in end to end abutting relation at the plane of the pistons and axially separable from each other, means for detachably connecting said rings to each other, reactance rings anti-frictionally mounted one in each stator ring and spaced axially from each other and accommodating the barrel flange and piston heads therebetween, reactance grooves in said reactance rings opening toward the barrel flange and receiving the laterally extending end portions of the pins for cooperation therewith to actuate the pistons, bores in said barrel flange positioned radially of the flange in alignment with the grooves, holes in each reactance ring in the groove thereof and opening toward the opposite reactance ring and extending parallel to the axis of rotation, each hole being aligned with a hole of the opposite reactance ring, cylindrical dowel pins extending through the barrel flange bores and received at their ends, one in each pair of aligned holes, and held in position by the reactance rings, and said dowel pins engaging the end walls of the associated bores for holding said reactance rings apart.
7. In a rotary radial piston pump or motor, a rotatable barrel having a plurality of radial cylinders, pistons in the cylinders respectively, valve means for the cylinders, each piston having a crosshead with a transverse bore therethrough parallel to the barrel axis, a flange on the barrel having radial ways respective to the crossheads, a rotary reactance means surrounding the barrel and mounted for adjustment to different positions of eccentricity relative thereto and including a pair of actuating rings spaced apart axially from each other for accommodating the piston crossheads therebetween with operative clearance, reactance grooves in the rings opening toward the pistons and aligned with each other, cross pins carried by the pistons respectively, each cross pin comprising a large diameter central portion substantially coextensive with the crosshead bore and anti-frictionally supported therein substantially continuously along its length, and end portions of less diameter extending axially of the pin from the large diameter portion beyond the radial limits of the respective piston heads and flange, whereby radial shoulders are formed on the cross pin at the juncture of said large and small diameter portions, said extending end portions being received in said grooves respectively, and said rings having radial faces alongside the pistons in relatively rolling engagement with said shoulders and constraining the pins from skewing about the axes of the associated pistons, respectively.
8. In a rotary radial piston pump or motor, a rotatable barrel having a plurality of radial cylinders, pistons in the cylinders respectively, valve means for the cylinders, each piston having a crosshead with a transverse bore therethrough parallel to the barrel axis, radial guide means on the barrel respective to the crossheads, a rotary reactance means surrounding the barrel and mounted for adjustment to different positions of eccentricity relative thereto and including means having walls spaced apart axially from each other for accommodating the piston crossheads therebetween with operative clearance, reactance grooves in the walls opening toward the pistons and aligned with each other, cross pins carried by the pistons respectively, each cross pin comprising a large diameter central portion anti-frictionally mounted in and substantially coextensive with the crosshead bore of the associated piston, and having end portions of less diameter extending axially of the pin from the large diameter portion beyond the limits of the associated piston head and the said guide means on the barrel, whereby radial shoulders are formed on each cross pin at the juncture of said large and small diameter portions of each pin, said extending end portions being received in said grooves respectively, said walls having radial face portions alongside the pistons in relatively rolling engagement with said shoulders and constraining the pins respectively from rotation about the axes of their associated pistons respectively, the said shoulders and reduced end portions being joined by a short radius curved surface, and the edges at the juncture of the grooves and said radial face portions being joined by a short radius curved surface different from first mentioned curved surface.
9. In a radial piston rotary reactance pump or motor including a casing, a rotor, piston and cylinder assemblies carried thereby, valve means for the assemblies, laterally extending thrust means carried by the assemblies, a reactance rotor operatively engaging the thrust means for operating the assemblies, said reactance rotor comprising a pair of complete self-contained anti-friction bearing assemblies positioned at opposite sides of the plane of the piston and cylinder assemblies, each bearing assembly including an outer race, an inner race and anti-friction elements carried thereby between said races, means independent of said casing rigidly connecting the outer races of said bearing assemblies together, said outer races being directly supported in the casing with the inner races in direct cooperation with said thrust means, and means for constraining said assemblies to proper operating position axially of the axis of rotation.
10. In a rotary radial piston pump or motor,

- a casing, a rotary reactance sub-assembly disposed within the casing and comprising a pair of self-contained anti-friction bearing assemblies, each bearing assembly comprising a stationary race member, a relatively rotatable one-piece race member coaxial therewith, and anti-friction elements between the race members and in direct rolling cooperation therewith, reactance grooves formed directly in the relatively rotatable race members and positioned inwardly toward the axes thereof from the elements, means independent of the casing for drawing and clamping the stationary race members together in fixed rigid co-axial relation with respect to each other with the rotatable race members spaced apart axially from each other and with the grooves of the rotatable race members aligned with each other, and means for mounting said subassembly in the casing.
- 20 11. In a rotary radial piston pump or motor, a casing, a rotary reactance sub-assembly disposed within the casing and comprising stationary race members, relatively rotating race members, anti-friction bearing elements in direct 25 rolling engagement with the associated stationary and relatively rotating race members and supporting each rotating member within an associated stationary member, said relatively rotating members having axially spaced radial 30 faces and normally aligned grooves in said faces, means on said members cooperating with the associated bearing elements for constraining each stationary race member and its associated relatively rotatable race member from relative 35 axial separation, said stationary members and associated rotating members with the associated bearing elements providing a pair of axially sep-

arable self-contained anti-friction bearing assemblies, means independent of said casing rigidly connecting said stationary race members together, and means mounting the subassembly in the casing.

12. In a reactance assembly for a radial piston pump or motor, a casing, a pair of stationary members, means independent of the casing rigidly connecting said stationary members together, rigid relatively rotating members carried one by each stationary member, sets of radial anti-friction bearing elements disposed between associated stationary and relative rotating members and in direct rolling engagement with adjacent surfaces of the members for supporting one within the other, said relatively rotating members being spaced axially from each other to provide an axial clearance space between adjacent faces of the relative rotating members, normally aligned grooves directly in said relatively 20 rotating members and opening through said adjacent faces and arranged radially with respect to the axis of said members close to the path of the bearing elements, said stationary and relatively rotating members having bearing grooves 25 receiving said anti-friction elements whereby said elements serve to maintain each stationary member and its associated relatively rotating member against axial separation and forming with the associated sets of radial antifriction 30 bearing elements a plurality of axially spaced and coaxially disposed separable self-contained complete anti-friction bearing sub-assemblies, and means mounting said pair of stationary members in the casing.
